UNITED STATES PATENT OFFICE.

CORNELIUS D. McGIEHAN, OF JERSEY CITY, NEW JERSEY.

ANTISLIPPING AND NON-WEARING MEDIUM.

No. 879,790.

Specification of Letters Patent.

Patented Feb. 18, 1908.

Application filed November 20, 1906. Serial No. 344,338.

To all whom it may concern:

Be it known that I, CORNELIUS D. McGIEHAN, a citizen of the United States, residing at Jersey City, in the county of Hudson and 5 State of New Jersey, have invented new and useful Improvements in Antislipping and Non-Wearing Mediums, of which the following is a specification.

This invention relates to anti-slipping and 10 non-wearing mediums for general use and particularly adapted for application or incorporation in stair, tread, horse-shoe, automobile shoe and other analogous structures, and consists essentially of a contacting or tread 15 member having an obdurate substance and a softer material both included in the member and exposed by a surface thereof.

The primary object of the invention is the 20 production of a contacting or tread member having both a very hard substance and a softer material therein to form a surface for full exposure having the characteristic of durability as well as anti-slipping qualities in one organization to insure resistance to 25 wear and sufficient adhesion with relation to the surfaces or devices engaged thereby to render the member economical and effective for obviating falls and skidding or sliding movements.

30 The accompanying drawings in part illustrate a particular use of the non-wearing and anti-slipping member, but it will be understood that the member is unlimited in its applications. Further, the contour, thickness 35 and other dimensions of the member are not essential, as the shape and dimensions may be varied indefinitely.

In the drawing:—Figures 1 and 2 represent detail views of two forms of the member 40 embodying features of the invention. Fig. 3 is a longitudinal vertical section of the member shown by Fig. 1. Fig. 4 is a plan view of a portion of a stair-tread shielding device or plate showing one application of the member. Fig. 5 is an edge elevation of the device 45 or plate shown by Fig. 4.

The numeral 1 designates the non-wearing and anti-slipping member composed of an obdurate material 2, such as carborundum, 50 adamite, emery or other hard, gritty substance, and a softer material 3 such as an artificial stone composition, a metal, a metallic alloy, or other material having anti-slipping or adhering qualities. As either carborundum, adamite, or emery possesses the desired 55 qualifications as an obdurate material and as

an artificial stone composition, a metal, or a metallic alloy have the necessary anti-slipping or adhering qualities, it is to be understood that in the claim the selection of the 60 substance "carborundum" for the obdurate material and the "metallic alloy" for the anti-slipping material are to be employed generically to cover all of the materials named in both instances. 65

The obdurate material and softer substance may be associated by any preferred method of procedure which will result in an exposed disposition thereof on one surface at least. The exposed surface embodying the 70 obdurate material and softer substance may also be either smooth or rough as the particular application of the member may demand, but it has been found by experiment that each will more effectively perform its 75 function if the surface be smooth. The exposed contact surface may be either flush with its holding means or be projected from the latter, and any device or structure may be utilized for securing the member against 80 movement.

As shown by Figs. 4 and 5, one of the advantageous uses of the member is for anti-slipping coverings of steps, and for this purpose a plurality of the members are secured 85 to a supporting body or plate 4 which in turn is adapted to be fastened on the tread of a step. It will be obvious that without the provision of some means for relieving such body or plate from accumulated dirt that 90 it will soon become filthy and unhealthful. To overcome this disadvantage, intersecting grooves 5 and 6 are formed between the members, the said grooves being in direct alignment and open fully through the opposite side and end edges of the body or plate to permit a broom or other cleaning device to be freely moved therein and force 95 the dirt out of the body edges. It is unnecessary that the members be formed rectangular as shown to render the grooves effective, as other shapes may be adopted and still preserve the continuity of the groove structure. The said grooves are also used 100 for self-draining purposes. 105

Numerous other applications might be described showing a beneficial result derived from the association and exposure in each member of the obdurate and softer substances, in contradistinction to other anti-slipping and non-wearing compositions and devices wherein either the obdurate sub- 110

stance alone has a surface exposure and held by the softer substance, or the obdurate and softer substances are used alone or arranged individually in the form of adjacent strips 5 or members.

What I claim is:

A tread device for steps comprising a base with the upper surface thereof upon the same plane throughout, a plurality of tread 10 members each consisting of a mass of carborundum and a metallic alloy, said tread members having flat lower faces, said flat lower faces of said tread members secured to the upper face of the base, said tread mem-

bers having the sides thereof beveled and uninterrupted throughout, the upper faces of said tread members further uninterrupted throughout said tread members disposed throughout the upper face of said base so as to form a series of transversely and longitudinally-extending intersecting grooves between said members.

In testimony whereof, I affix my signature in presence of two witnesses.

CORNELIUS D. McGIEHAN.
